McCabe & Pierce Atty's

UNITED STATES PATENT OFFICE.

GEORGE L. HUNT, OF BOSCOBEL, WISCONSIN, ASSIGNOR TO THE GEORGE L. HUNT MANUFACTURING COMPANY, INC., OF BOSCOBEL, WISCONSIN, A CORPORATION OF WISCONSIN.

GEAR PULLER.

Application filed April 20, 1922. Serial No. 555,760.

To all whom it may concern:

Be it known that I, GEORGE L. HUNT, a citizen of the United States, and resident of Boscobel, in the county of Grant and State of Wisconsin, have invented a certain new and useful Improvement in Gear Pullers, of which the following is a full, clear, concise, and exact description, reference being had to the accompanying drawings, forming a part of this specification.

My invention relates to a tool which may be employed in drawing gears or other wheels from their shafts or axles.

Among its objects, my invention contemplates the provision of a gear puller of sturdy construction, that comprises a relatively small number of parts, which may be readily operated by one man and which may be economically manufactured.

Another object of the invention is to provide a gear puller which may be employed in removing gears of various sizes and which comprises gear-engaging elements or jaws which, when the tool is operated, tend to approach each other and thus to clamp the gear which is being removed.

In the accompanying drawings illustrating a preferred embodiment of my invention,

Figure 1 is an elevational view illustrating the gear puller of my invention as it appears when used for pulling a gear from its associated shaft;

Figure 2 is an elevational view taken at right angles to the plane of Figure 1;

Figure 3 is a top plan view of the devices shown in Figures 1 and 2; and

Figure 4 is an elevational view of one of a pair of gear-engaging elements, or jaws, which may be substituted for the corresponding jaws shown in the preceding figures.

Similar characters of reference refer to corresponding parts throughout the several views.

Referring to the drawings, reference numeral 10 indicates a jack-screw which is provided at its lower end with a centering point 11 and at its upper end with a square head 12 to facilitate the application of a wrench or other tool wherewith the screw may be rotated. Screw 10 extends through and has threaded engagement with a block or hub 13 which is formed integral with arms 14—14 which project in opposite directions from the block in lines at right angles to the axis of screw 10.

Carried by the arms 14 at the outer ends thereof are the jaw shackles 15—15, each of these jaw shackles being formed from a single piece of metal and comprising the substantially triangular spaced-apart sides 60 15^a—15^a connected by web 15^b. A rivet 16 pivots the apices of the triangular sides of each jaw shackle to one of the arms 14.

The gear-engaging jaws are illustrated at 17—17, each of these jaws having the upper end thereof embraced by one of the jaw shackles 15. Each jaw is pivoted in its associated shackle 15 by a bolt 18. It will be noted that the jaws 17 are provided with wide faced hook portions 17^x. In some cases, 70 it is desirable to employ jaws having narrow faced hook portions. Such a modified jaw construction is illustrated in Figure 4. I have illustrated bolts 18—18 as means for pivoting paws 17 in their associated shackles, 75 this arrangement permitting the jaws 17 to be interchanged with jaws of the type illustrated in Figure 4. Of course, bolts 18—18 may be replaced by suitable rivets, if desired.

At A I have illustrated a gear that is to 80 be withdrawn from its shaft B. In order to remove the gear, the hook portions 17^x of the jaws are caused to engage behind, or under, the gear A and jack-screw 10 is screwed down so that its centering point 11 85 engages the adjacent end of shaft B. Continued turning down of the jack-screw moves the block or hub 13 upwardly or away from shaft B. As the hub or block 13 moves upwardly, the shackles 15 are permitted to 90 move relative to arms 14 around the axes of rivets 16, and to move relative to their associated jaws 17 until the shackle portions 15^b are drawn into snug engagement with the outer edges of the upper portions of the 95 jaws. By virtue of this construction, the thrust imparted to block or hub 13 is resolved into two components, namely, one which tends to draw the gear A off of its shaft B and the other which tends to cause 100 the hooked ends of the jaws tightly to engage the gear A.

Having thus illustrated and described a preferred embodiment of my invention, what I claim as new, and desire to secure by 105 Letters Patent of the United States, is:

1. A gear puller comprising a jack-screw, a block through which said jack-screw extends and with which it has threaded engagement, said block being provided with 110

2
a pair of fixed arms which project therefrom in opposite directions in lines substantially at right angles to the axis of the jack-screw, a pair of jaw shackles, each of said jaw shackles being substantially U-shaped in horizontal cross section and having its parallel portions pivoted to one of said fixed arms for movement relative to the latter in a plane co-incident with the axis of the jack-screw, and a pair of jaws depending from said shackles, the upper end of each of said jaws being embraced within one of said shackles and being pivoted to its associated shackle, near the upper portion of the shackle, for limited movement relative to the shackle in a plane co-incident with the axis of the jack-screw.

2. A gear puller comprising a block, a jack-screw extending through and having threaded engagement with the block and being provided at its upper end with means to facilitate its rotation, a pair of jaw shackles pivoted to the block on opposite sides of the latter, said shackles adapted to move relative to the block in a plane parallel to the axis of the jack-screw, a pair of gear engaging jaws, each jaw being pivoted to one of said shackles at a point above the point where such shackle is pivoted to the block, and means carried by each shackle for limiting the movement between the shackle and its associated jaw.

3. A gear puller comprising a jack-screw, a block through which the jack-screw ex-

tends and with which it has threaded engagement, a pair of oppositely disposed jaw shackles, each pivoted to the block for movement relatively to the latter in a plane co-incident with the axis of the jack-screw, each of said shackles being substantially U-shaped in horizontal cross section and having its parallel legs extending toward the block and pivoted thereto as aforesaid, together with a pair of jaws depending from said jaw shackles, the upper end of each of said jaws being held within the embrace of one of said shackles.

4. A gear puller comprising a jack screw, a block through which the jack screw extends and with which it has threaded engagement, a pair of links each pivoted to said block, a pair of jaws, one depending from each of said links, each link being pivoted to the upper end of its associated jaw for limited swinging movement relative thereto and being conformed to engage said jaw, at a point a substantial distance below the point where the jaw and link are pivotally connected, when the link swings relatively to the jaw in response to upward movement of the block resulting from actuation of the jack screw.

In witness whereof, I hereunto subscribe my name this 12th day of April, 1922.

GEORGE L. HUNT.
